UNITED STATES PATENT OFFICE.

ROBERT E. WEBER, OF MILWAUKEE, WISCONSIN.

RESONANCE-CHAMBER FOR TALKING-MACHINES.

1,319,739.

Specification of Letters Patent. Patented Oct. 28, 1919.

Application filed May 25, 1916. Serial No. 99,711.

To all whom it may concern:

Be it known that I, ROBERT E. WEBER, a citizen of the United States, residing at Milwaukee, county of Milwaukee, and State of Wisconsin, have invented new and useful improvements in Resonance-Chambers for Talking-Machines, of which the following is a specification.

My invention relates to improvements in resonance chambers for talking machines.

The object of my invention is to provide means for improving the tone, amplifying the sound volume, and eliminating discordant sounds, such, for example, as the scratching sound commonly attributed to the friction of the needle upon the surface of the record.

In the drawings—

Figure 1 is a vertical sectional view of a portion of a talking machine of the so called cabinet type equipped with my invention, said section being drawn to a plane cutting the axis of the horn, the machine illustrated being of that type in which the horn is in closed within the cabinet.

Fig. 2 is a front elevation of the resonance chamber.

Fig. 3 is a vertical sectional view of the front wall of a talking machine cabinet showing my invention applied thereto in modified form adapted to be used as an attachment to a previously constructed cabinet.

Fig. 4 is a central longitudinal sectional view of my improved resonance chamber as illustrated in Fig. 3.

Fig. 5 is a front elevation of the same.

Like parts are identified by the same reference characters throughout the several views.

The cabinet 1 illustrated in Fig. 1, is of ordinary construction, but the horn 2 preferably has wooden walls, spruce being preferred. The outer or large end of the horn is formed to receive my improved resonance chamber 3, the top and bottom walls of the chamber being secured to the horn by screws 4. The inner wall 5 of the resonance chamber is provided with an elongated aperture or slot 6 adapted to allow the free transmission of the sound waves to the chamber.

The front wall 7 constitutes the main sounding board. This wall is thin and is provided with *f* holes 10, similar to those formed in the top wall of a violin. The inner surface of this front wall is provided with a bass bar 12, which, in the construction

illustrated in Figs. 1 and 2, is located midway between two pairs of *f* holes 10 and extends transversely across the front wall to points near its side margins. The bar 12 is 60 tapered toward its respective ends and serves as a tone agent. A sound post 13 may also be employed to connect the back plate 5 with the front plate or wall 7. It will be understood that the sound waves received in resonance chamber are utilized to set the front and rear walls of the chamber in vibration in substantially the same manner that the walls of a violin vibrate. The corners or angles formed at the junction of the walls 70 5 and 7 with the side and end walls, are preferably filled in to present rounded surfaces, as shown at 15, and the side and end walls are preferably thick enough to provide a solid frame for the chamber and facilitate 75 connecting the same rigidly to the walls of the horn. The outer surface of the frame is rectangular and the walls of the horn are arranged to form a rectangular opening to receive the resonance chamber. 80

It will be understood by those familiar with this art that the body of the resonance chamber and the air contained therein being thus set in vibration, communicates this vibration to the circumambient air. The 85 body of the resonance chamber acting as a sounding board reinforces all the notes within its compass, whereas discordant sounds of minor character will be neutralized or eliminated. 90

It is not essential that the resonance chamber should be attached directly to or within the mouth of the horn. In Figs. 3 and 4, I have illustrated a resonance chamber, which is particularly adapted to be adjusted to or partially within the sound opening 17 of a so called talking machine cabinet. In this case the chamber is secured directly to the walls of the cabinet at the margins of the sound opening and projects outwardly for a short distance therefrom. The resonance chamber illustrated in Figs. 3 and 4 is also provided with a different arrangement of the *f* holes and a pair of bass bars or sounding bars 12' are employed between the two *f* holes 10' 100 illustrated. These sounding bars 12' diverge in general conformity to the divergence of the *f* holes. The specific arrangement of the *f* holes and bass bars is not essential to my invention, these features being subject to a number of variations, the character of which will be well understood by those 110

skilled in this art. A symmetrical arrangement is, however, desirable.

I claim—

The combination with a talking machine 5 having a sound amplifying chamber provided with openings for the escape and admission of sound waves, of a resonance chamber disposed across said opening and having an inner wall provided with an opening 10 adapted to freely admit sound waves to said chamber, said opening in the resonance chamber being larger than the sound admis-

sion opening of said amplifying chamber, and an outer vibratory wall extending directly across the path of the sound waves, 15 provided with relatively small openings on opposite sides of the center, through which the amplified sound waves may be projected.

In testimony whereof I affix my signature in the presence of two witnesses.

ROBERT E. WEBER.
